D. S. KENNEDY.

TYPOGRAPHICAL DISTRIBUTING MACHINE.

APPLICATION FILED MAR. 29, 1919.

1,387,495.

Patented Aug. 16, 1921.

UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING-MACHINE.

1,387,495.

Specification of Letters Patent. Patented Aug. 16, 1921.

Original application filed November 30, 1917, Serial No. 204,534. Divided and this application filed March 29, 1919. Serial No. 286,220.

To all whom it may concern:

Be it known that I, DAVID S. KENNEDY, a citizen of the United States, residing at Brooklyn, in the county of Kings and State 5 of New York, have invented certain new and useful Improvements in Typographical Distributing-Machines, of which the following is a specification, reference being had therein to the accompanying drawing, being 10 a division of original application filed November 30, 1917, Ser. No. 204,534.

My invention relates to typographical machines, such as linotype machines of the general organization represented in Letters 15 Patent of the United States to O. Mergenthaler, No. 436,532, wherein circulating matrices are released from a magazine in the order in which their characters are to appear in print and then assembled in line, the 20 composed line transferred to the face of a mold, the mold filled with molten metal to form a slug or linotype against the matrices which produce the type characters thereon, and the matrices thereafter returned 25 through a distributing mechanism to the magazine from which they started.

My present invention is directed to improvements in the distributing mechanism of such machines, as will be fully set forth 30 in the detailed description to follow. These improvements are particularly useful in connection with machines handling matrices with characters of greatly increased size or "point," such as are used in advertising matter or display work, which machines are exemplified in my pending application, Serial No. 204,534, filed November 30, 1917, of which the present application is a division.

40 In the accompanying drawings, I have shown my improvements in preferred form and by way of example and as applied to a machine of the kind noted. It will be obvious, however, that they may be embodied 45 in other forms and applied to machines of other constructions without departing from the spirit of my invention. Generally speaking, I desire it to be understood that I do not limit myself to any specific form 50 or embodiment, except in so far as such limitations are specified in the claims.

Referring to the drawings:

Figure 1 is a vertical section on an enlarged scale taken through the distributing

mechanism including the magazine entrance;

Fig. 2 is a section on the line 2—2 of Fig. 1;

Fig. 3 is a view similar to Fig. 1 and illustrating a modification;

Fig. 4 is a section on the line 4—4 of Fig. 3; and

Fig. 5 is a perspective view of one of the matrices employed.

The matrices X are stored in the magazine A, to which they are returned after casting by the distributing apparatus. This apparatus, with the exception hereinafter noted, is precisely the same as that presented in my Letters Patent No. 1,266,022. It comprises, as usual, the longitudinal bar or rail F along which the matrices are conveyed by the rotating screws F¹. The bar is of the usual form, being of V-shape in cross section and provided with a series of successive tooth or distributor combinations which control the release of the matrices at the required points according to character for return to their proper channels in the magazine. As the matrices are released from the distributor bar, they drop into a magazine entrance F² the channels of which are constituted by sets of opposing grooves F³ formed in the inner faces of its side plates and extending throughout the length thereof. As in my Letters Patent, these sets of grooves F³ are disposed in direct alinement with or in the vertical planes of the releasing points of the bar combinations. It may be noted that the tooth combinations are disposed at unequal distances apart on the distributor bar and that the entrance grooves are similarly spaced to correspond.

The matrices X are formed, as usual, with pairs of projecting ears X¹ of substantially uniform thickness throughout the font, and are also provided at their upper ends with thin web portions X² containing tooth or distributing combinations adapted to cooperate with those on the bar F. As explained in my said patent, the matrices X differ from those in common use only in respect to the location of the combination web X², which as therein shown and described are located at the forward sides of the matrices and in the vertical planes of the projecting ears. In the distribution of the matrices, therefore, those released from

the distributor bar at any given point present their projecting ears X^1 in the same position, viz., in a vertical plane passing through the releasing point of the bar combination and the underlying entrance groove F^3 , and are consequently directed into the latter irrespective of the relative thicknesses of the matrix bodies, thus adapting the machine to distribute matrices of all sizes and 10 fonts.

Thus far the distributing apparatus is the same as presented in my Letters Patent. My present improvements are directed to means for insuring the proper entrance or 15 delivery into the entrance grooves F^3 of the projecting ears of the matrices as the latter are disengaged or released from the distributor bar. The objection sought to be overcome is that the matrices at or about 20 the time of their release from the bar have a tendency to assume a tilted or inclined position, due to the fact that their tooth combinations are disposed to one side of the center of gravity such as to cause the 25 matrices to swing. In the form illustrated in Figs. 1 and 2, this difficulty is overcome by providing the rear or bottom side plate of the magazine entrance with a short upward extension F^4 which passes beyond the 30 matrices while in course of distribution and terminates close up to their upper projecting ears. This extension F^4 is formed with grooves F^5 which constitute continuations of the main entrance grooves F^3 , but which 35 are separated therefrom by a transverse groove or channel F^6 , wherein the lower projecting ears of the matrices travel during their journey through the distributor. Due 40 to this arrangement, when the matrices are released from the bar, their lower ears immediately enter the main entrance grooves F^3 , while their upper ears engage in the grooves F^5 of the extension F^4 . No opportunity is thus given the matrices to assume 45 abnormal positions such as would prevent their upper ears from entering the main entrance grooves. If desired, the grooves F^3 and F^5 may be flared at their upper ends to facilitate the entrance of the matrix ears, 50 as indicated in Fig. 2.

Figs. 3 and 4 illustrate a modification of the above feature. As shown in these figures, the magazine entrance F^2 is provided at its upper end with a series of short 55 partition plates F^7 , which are preferably fixed in position so that their left side faces will be flush with the right side walls of the entrance grooves, the opposite side walls of which in the form here illustrated are 60 beveled or flared toward the end of the magazine so as to make the entrance grooves at their receiving ends substantially as wide as the distance between the adjoining partition plates. In this form, when the matrices are 65 released from the distributor bar, their lower

ends pass immediately between two adjoining partition plates, which thus guide them in a straight path along the grooved channels and prevent their toppling over to one side or the other such as would prevent the 70 upper ears from entering the grooves. In both forms, when the projecting ears of the matrices at their opposite ends once become engaged in the entrance grooves, the matrices are under positive and absolute control and are guided directly into the magazine channels in a definite position irrespective of thickness. 75

At its lower end, immediately adjacent the magazine, a section F^8 of the front or top plate of the entrance is arranged to be swung outward about the pivot F^9 . If, therefore, any matrices should accidentally become lodged in the entrance or between it and the magazine, the plate is free to be swung 80 outward to permit the removal of the offending matrices, or to yield in the event that the magazines are shifted when the matrices are so lodged. 85

As previously stated, I have shown my improvements merely in preferred form and by way of example and as applied to the particular kind of machine described, but it will be obvious that many modifications and alterations will readily suggest themselves 90 to those skilled in the art without departing from the scope of the invention. 95

Having thus described my invention, its construction and mode of operation, what I claim and desire to secure by Letters Patent of the United States is as follows:— 100

1. In a typographical machine comprising matrices formed with projecting ears at their upper and lower ends, the combination with a channeled magazine to contain the matrices, a distributor, and an intermediate magazine entrance separate and distinct from the magazine and formed with sets of opposing grooves to guide the matrices by their projecting ears from the distributor to the magazine, of supplemental guiding means forming part of said magazine entrance and arranged at the receiving end thereof to insure the engagement of the upper ears of the matrices in the entrance 105 grooves. 110

2. In a typographical machine comprising matrices formed with projecting ears at their upper and lower ends, the combination with a channeled magazine to contain the matrices, a distributor, and an intermediate magazine entrance separate and distinct from the magazine and formed with sets of opposing grooves to guide the matrices by their projecting ears from the distributor to the magazine, of supplemental guiding means arranged at the receiving end of the magazine entrance to insure the engagement of the upper ears of the matrices in the entrance 115 grooves, the said means consisting of 120

a grooved plate whose grooves register with and are the same in width as those of the magazine entrance and which extend above the lower ends of the matrices during their travel through the distributer and in a position to engage their upper projecting ears when released from the distributer.

3. In a typographical machine comprising matrices each formed with a distributing combination and with projecting ears at its upper and lower ends, the said combination and projecting ears being located in the same longitudinal plane, the combination with a channeled magazine wherein the matrices are stored, a distributer having a series of combinations to coöperate with those of the matrices, and a magazine entrance separate and distinct from the magazine and formed with sets of opposing grooves lying in vertical planes passing through the releasing points of the distributer combinations, of supplemental guiding means forming part of said magazine entrance and arranged at the receiving end thereof to insure the en-

gagement of the upper ears of the matrices 25 in the entrance groove.

4. A structure as specified in claim 3, characterized by the fact that the supplemental guiding means are constituted by one of the side plates of the magazine entrance which is extended upward beyond the lower ends of the matrices while in course of distribution and formed with grooves registering with and of the same width as the entrance grooves proper but separated 30 therefrom by a longitudinal channel wherein the lower ears of the matrices travel during distribution, in the manner and for the purpose described.

5. A structure as specified in claim 4, 40 characterized by the fact that the magazine entrance grooves proper and those in the extended side plate of the entrance are flared at their upper ends.

In testimony whereof I have affixed my 45 signature hereto.

DAVID S. KENNEDY.
